CLARENCE S. SNAVELY, OF PITTSBURGH, AND ARTHUR W. FISHER, OF WILKINSBURG, PENNSYLVANIA, ASSIGNEES TO THE UNION SWITCH & SIGNAL COMPANY, OF SWISSVALE, PENNSYLVANIA, A CORPORATION OF PENNSYLVANIA.

RAILWAY APPARATUS.

Application filed June 6, 1923. Serial No. 643,767.

Our invention relates to railway apparatus. Apparatus embodying our invention is particularly well adapted for use in connection with highway crossing signals which are governed by train controlled track circuits, although it is not limited to this specific use.

We will describe one form of apparatus embodying our invention, and will then point out the novel features thereof in claims.

The accompanying drawing is a diagrammatic view showing one form of apparatus embodying our invention.

Referring to the drawing, the reference characters 2 and 2^a designate the track rails of a railway over which traffic moves in both directions, and which railway intersects a highway M—N at point B. The rails 2 and 2^a are divided into two insulated track sections A—B and B—C by means of insulated joints 1, the point of division of these two sections being located adjacent the highway crossing. Each track section is provided with a source of track circuit energy which comprises a battery G connected across the rails at an intermediate point in the section. Interposed between the battery G and one rail 2^a of each section is a resistance 3 one function of which is to limit the output of the battery when its terminals are short-circuited by the wheels and axles of a train occupying the associated section.

Each section is also provided with two track relays one located at each end of the section, and designated by the reference character R with a distinguishing exponent V. Referring particularly to section B—C, track relay R³ located at the left hand end of the section is provided with a pickup circuit which passes from rail 2^a through wires 9 and 8, front contact 7 of a slow acting relay D³, wires 6 and 5, winding of relay R³, and wire 4 to rail 2. This circuit is closed only when relay D³ is energized. Track relay R³ is also provided with a stick or holding circuit which passes from rail 2^a through wires 9 and 12, front contact 11 of relay R³, wires 10 and 5, winding of relay R³ and wire 4, to rail 2. This circuit is closed only when relay R³ is already energized so that it serves as a holding circuit for maintaining relay R³ in its energized condition but is effective only when the relay has been previously

energized over its pickup circuit. Track relay R⁴ located at the right hand end of section B—C is controlled by circuits similar to those just described for relay R³.

Associated with relay R³ is a slow acting relay C³ which is arranged to be energized when relay R³ is de-energized. The circuit for relay C³ passes from battery H³ through wire 24, back contact 25 of track relay R³, wire 26, winding of relay C³, and wires 27 and 28 back to battery H³. Slow acting relay D³ is in turn controlled by relay C³ over a circuit which passes from battery H³ through wires 24 and 29, front contact 30 of relay C³, wire 31, winding of relay D³, and wires 32, 33 and 28 back to battery H³. This circuit is closed only when relay C³ is energized. It is therefore clear that if relay R³ is de-energized, relay C³ is energized and relay C³ in turn causes D³ to become energized, thus completing the pickup circuit for relay R³. It follows that after a de-energization of relay R³ the relay can not be picked up again till relay D³ closes its front contact.

The apparatus associated with each track relay R³, R² and R⁴ is the same as that associated with relay R³.

An interlocking relay L of any suitable form is located adjacent to point B and comprises two windings 35 and 36. This relay controls a suitable warning signal such as an electrically operated bell K. The bell K is provided with one circuit which passes from a battery J, through wire 52, operating mechanism of bell K, wire 51, back contact 50 operated by winding 36 of relay L, and back to battery J. Another circuit is provided which passes from battery J, through wire 52, operating mechanism of bell K, wire 53, back contact 54 operated by winding 35 of relay L, and back to battery J. The winding 36 of interlocking relay L is provided with a circuit which passes from battery H⁴, through wire 13, front contact 14 of track relay R⁴, wire 15, back contact 16 of slow acting relay D⁴, wire 17, back contact 18 of slow acting relay D⁴, wire 19, front contact 20 of track relay R⁴, wire 21, winding 36 of relay L, and wires 22 and 23 back to battery H⁴. It is clear that this circuit is closed only when relays R³ and R⁴ are energized and relays D³ and D⁴ are de-energized. Winding 35 of relay L is similarly

controlled by relays R' , R^2 , D' and D^2 in section A—B.

As shown in the drawing all the parts are in the positions corresponding to an unoccupied condition of the portion of track shown in the drawing. Under these circumstances each track relay R is energized over its stick circuit, and relays C and D are all de-energized. The pickup circuit for each track relay R is therefore open at front contact 7 of the associated relay D . Both windings 36 and 35 of interlocking relay L are energized and bell K controlled by relay L is therefore de-energized.

We will now assume that a train moving toward the left enters section B—C. Relays R^3 and R^4 will be immediately de-energized thus breaking the circuit for winding 36 of interlocking relay L at their front contacts 14 and 20, respectively. Back contact 50 of relay L is therefore closed, thus completing the circuit for bell K which commences to ring. The de-energization of each track relay causes the associated slow acting relay C to become energized. The closing of the front contact of each relay C completes the circuit for the associated slow acting relay D which thereupon becomes energized. The closing of the front contact of each relay D closes the pickup circuit for the associated track relay R . The track relays R do not, however, become energized due to the presence of the train in the section.

As the train enters section A—B, the apparatus associated with this section functions in precisely the same manner as just described in connection with the apparatus associated with section B—C. Relay L is so constructed however that contact 54 does not close if winding 35 becomes de-energized before winding 36 is re-energized, and so the bell will stop ringing as soon as the rear end of the train passes point B and winding 36 becomes energized.

As the rear of the train leaves section A—B, track relays R^3 and R^4 become energized over their pickup circuits and are subsequently maintained in their energized condition by their stick circuits. The energization of each track relay R opens the circuit for the associated slow acting relay C . After a considerable interval of time these relays C open their front contacts and close their back contacts, thus opening the energizing circuits for the associated slow acting relays D . The closing of the back contact 30 of relay C^3 completes a shunt around relay D^3 comprising wires 32 and 34, back contact 30 of relay C^3 , and wire 31, which shunt further retards the action of slow acting relay D^3 . The action of relay D^4 is similarly retarded. After an interval of time, relays D close their back contacts, thus completing the circuit for winding 36 of relay L which thereupon becomes energized.

Back contact 54 of relay L remains locked in its open position, however, and hence the energization of winding 36 and the consequent opening of back contact 50 controlled thereby results in opening the circuit for bell K which stops ringing.

As the train moves out of section A—B, the track relays R' and R^2 become energized, thus causing relays C' and C^2 to become de-energized. After a time interval the circuits for relays D' and D^2 are interrupted and low resistance shunts connected across their terminals as described in connection with relay D^3 . After a time interval relays D' and D^2 become de-energized thus closing the circuit for winding 35 of relay L . The energization of this winding picks up the contact 54 and restores the apparatus to its normal condition.

The operation of the apparatus for traffic moving from left to right is the same as just described for traffic from right to left and will be readily understood without further explanation.

The advantages of our invention are as follows:

It has been observed that under certain conditions the shunting of track relays by a car or train is uncertain and subject to interruption; this condition may arise, for examples, when a track section is occupied by light rolling stock, or when the rails of the section are rusty. Under this condition the track relays may be alternately opened and closed, and when a highway crossing signal is controlled only by the track relays such alternate opening and closing will usually cause the signal to alternately operate and cease to operate.

Referring now to track section B—C in the accompanying drawing, we will assume that the section is occupied by a vehicle, that track relays R^3 and R^4 have been initially de-energized, thereby closing the associated relays C and D , and that the vehicle momentarily ceases to shunt the track relays. The track relays R^3 and R^4 will immediately close and thereby close at contacts 20 and 14 the energizing circuit for winding 36 for the interlocking relay L , but this circuit remains open at back contacts 18 and 16 of relays D^3 and D^4 until the two last-mentioned relays become opened. Owing to the slow-releasing characteristics of relays C and D , contacts 18 and 16 will not close until the expiration of a considerable interval of time after the closing of relays R^3 and R^4 , and if this time interval is greater than the time interval during which the shunting action of the vehicle is ineffective, the circuit for winding 36 will remain open and the operation of the crossing signal K will not be interrupted. If the time interval created by the two slow acting relays C and D is not sufficient to bridge the maxi-

5   imum period during which the shunting action of a vehicle is ineffective, additional slow acting relays may be used for each track relay, the additional slow-acting relays being controlled in cascade in the same way that each relay D is controlled by the associated relay C in the drawing.

10   Assuming now that a train or vehicle moving toward the left occupies section A—B, it will be remembered that contact 54 of the interlocking relay L is open because winding 35 became de-energized before winding 36 became re-energized. If winding 35 should now become momentarily energized and subsequently de-energized, contact 54 would close, thereby causing operation of the crossing bell K even though the train or vehicle is moving away from the point B where the highway intersects the railway. Such momentary energization of winding 35 is prevented, however, because even though the shunting action of the train or vehicle may fail momentarily, the circuit for this winding will remain open at the back contacts of relays D' and D'', and it is assumed that these contacts will not close during the interval in which the track relays R' and R'' are closed.

15   Although we have herein shown and described only one form and arrangement of railway apparatus embodying our invention, it is understood that various changes and modifications may be made therein within the scope of the appended claims without departing from the spirit and scope of our invention.

20   Having thus described our invention, what we claim is:

25   1. In combination, a highway, a railway track intersecting said highway and provided with two track sections extending in each direction from the highway, a relay for each section provided with a holding circuit, means responsive to a train in each section for opening the holding circuit for the associated relay, a slow acting relay for each section controlled by the associated relay, a second slow acting relay for each section controlled by the associated first slow 30 acting relay, a pick-up circuit for each of said first relays controlled by the associated second slow acting relay, an interlocking relay having two magnets one for each section, means for controlling each magnet by the first relay and the second slow acting relay of the associated section, and a highway crossing signal controlled by said interlocking relay.

35   2. In combination, a highway, a railway track intersecting said highway and provided with two track sections extending in each direction from the highway, a relay for each section provided with a holding circuit, means responsive to a train in each section for opening the holding circuit for

the associated relay, a slow acting relay for each section, a pick-up circuit for each first relay controlled by the associated slow acting relay, means operating to energize each slow acting relay when the associated first 70 relay is open, an interlocking relay having two magnets one for each section, means for controlling each magnet by the two relays for the associated section, and a highway crossing signal controlled by said interlocking relay.

40   3. In combination, an insulated section of railway track, a track relay and a first and a second slow acting relay located at each end of said section, a source of energy connected across the rails of the section, a circuit for each track relay including the rails of the section and a front contact of said track relay, a second circuit for each track relay including the rails of the section and a front contact on the associated second slow acting relay, a circuit for each said first slow acting relay including a source of energy and a back contact on the associated track relay, a circuit for each said second slow acting relay including a source of energy and a front contact on the associated first slow acting relay, an electro-responsive device; and a circuit for said device including a source of energy, a front contact on each of said track relays, and a back contact on each said second slow acting relay.

45   4. In combination, a section of railway track, a source of energy connected across the rails of said section, a track relay connected with the rails of said section, a slow acting relay controlled by said track relay and arranged to be energized when said track relay is de-energized, a pick-up circuit for said track relay including a front contact on said slow acting relay, and a retaining circuit for said track relay including its own front contact.

50   5. In combination, a section of railway track, a source of energy connected across the rails of said section, a track relay connected with the rails of said section, a slow acting relay controlled by said track relay and arranged to be energized when said track relay is de-energized, a pick-up circuit for said track relay including a front contact on said slow acting relay, a retaining circuit for said track relay including its own front contact, and an electro-responsive device controlled by said track relay and said slow acting relay.

55   6. In combination, a section of railway track, a source of energy connected across the rails of said section, a track relay connected with the rails of said section, a slow acting relay controlled by said track relay and arranged to be energized only when said track relay is de-energized, and an electro-responsive device controlled by said track relay and said slow acting relay.

7. In combination, an insulated section of railway track, a track relay and a first and a second slow acting relay located at each end of said section, a source of energy connected across the rails of the section, a circuit for each track relay including the rails of the section and a front contact of said track relay, a second circuit for each track relay including the rails of the section and a front contact on the associated second slow acting relay, a circuit for each first slow acting relay including a source of energy and a back contact on the associated track relay, a circuit for each said second slow acting relay including a source of energy and a front contact on the associated first slow acting relay, a low resistance shunt for each said second slow acting relay including a back contact on the associated first slow acting relay, and an electro-responsive device controlled by said track relay and said second slow acting relay.
8. In combination, a section of railway track, a relay provided with a holding circuit, means responsive to the presence of a train in said section for opening said holding circuit, a pickup circuit for said relay including a front contact of a slow acting relay, means operating to energize said slow acting relay when said first relay is de-energized, and an electro-responsive device controlled by said slow acting relay.
9. In combination, a section of railway track, a relay provided with a holding circuit, means responsive to the presence of a train in said section for opening said holding circuit, a pickup circuit for said relay including a front contact of a slow acting relay, means operating to energize said slow acting relay when said first relay is de-energized, an interlocking relay controlled by said slow acting relay, and an electro-responsive device controlled by said interlocking relay.
10. In combination, a section of railway track, a relay provided with a holding circuit, means responsive to the presence of a train in said section for opening said holding circuit, a pickup circuit for said relay including a front contact of a slow acting relay, means operating to energize said slow acting relay when said first relay is de-energized, and an electro-responsive device controlled by said slow acting relay and by said first relay.
11. In combination, a section of railway track, a relay provided with a holding circuit, means responsive to the presence of a train in said section for opening said holding circuit, a pick-up circuit for said relay including a front contact of a slow acting relay, means operating to energize said slow acting relay when said first relay is de-energized, an interlocking relay controlled by said interlocking relay, and a signal controlled by said slow acting relay, and a signal controlled by said interlocking relay.
12. In combination, a section of railway track, a relay provided with a holding circuit, means responsive to the presence of a train in said section for opening said holding circuit, a slow acting relay controlled by said first relay, a second slow acting relay controlled by said first slow acting relay, a pickup circuit for said first relay including a contact of said second slow acting relay, and a highway crossing signal controlled by said second slow acting relay.
13. In combination, a section of railway track, a relay provided with a holding circuit, means responsive to the presence of a train in said section for opening said holding circuit, a slow acting relay controlled by said first relay, a pickup circuit for said first relay controlled by said slow acting relay, and an electro-responsive device controlled by said slow acting relay.
14. In combination, a section of railway track, a source of current connected across the rails of said section, a track relay connected across the rails of said section with a front contact of the relay interposed in the connection between the relay and one rail, a shunt around said front contact including a front contact of a slow acting relay, means operating to energize said slow acting relay when said track relay is de-energized, and an electro-responsive device controlled by said slow acting relay.
15. In combination, a section of railway track, a source of current connected across the rails of said section, a track relay connected across the rails of said section with a front contact of the relay interposed in the connection between the relay and one rail, a slow acting relay controlled by said track relay, a shunt around said front contact controlled by said slow acting relay, and a highway crossing signal controlled by said slow acting relay.
16. In combination, a highway, a railway track intersecting said highway and provided with two track sections extending in opposite directions from the highway, a source of track circuit current for each section, a track relay for each section, a slow acting relay for each section controlled by a back contact of the associated track relay, an interlocking relay having two windings one for each track section, a circuit for each winding controlled by a front contact of the track relay and a back contact of the slow acting relay for the corresponding section, and a highway crossing signal controlled by said interlocking relay.
17. In combination, a highway, a railway track intersecting said highway and provided with two track sections extending in opposite directions from the highway, a

- track circuit for each section including a source of current adjacent the middle of the section and a track relay adjacent each end of the section, a slow acting relay for each track relay and controlled by a back contact of the associated track relay, an interlocking relay having two windings one for each track section, a circuit for each winding controlled by a front contact of each track relay for the associated section and also by a back contact of each slow acting relay for the associated section, and a highway crossing signal controlled by said interlocking relay.
18. In combination, a track circuit including a track relay connected with the rails through a front contact thereof, a branch around said front contact including a normally open contact of an auxiliary relay, means for causing operation of said auxiliary relay to close said normally open contact when the track relay opens and to open said normally open contact when the track relay closes, the operation of said auxiliary relay to open said normally open contact requiring a considerable interval of time, and signaling apparatus controlled by said auxiliary relay.
19. In combination, a track circuit including a track relay connected with the rails through a front contact thereof, a branch around said front contact including a normally open contact of a slow acting relay, means for causing operation of said slow acting relay to close said normally open contact when the track relay opens and to open said normally open contact when the track relay closes, and signaling apparatus controlled by said slow acting relay.
20. In combination, a track circuit including a track relay connected with the rails through a front contact thereof, a branch around said front contact including a front contact of a normally de-energized slow acting relay, a circuit for said slow acting relay controlled by a back contact of said track relay, and signaling apparatus controlled by said slow acting relay.
21. In combination, a section of railway track, a first relay provided with a holding circuit including a front contact thereof, means responsive to the presence of a train in said section for de-energizing said first relay, a pick-up circuit for said first relay including a normally open contact of a slow acting relay, means for setting said slow acting relay into operation when said first relay becomes de-energized, and signaling apparatus controlled by said slow acting relay.
22. In combination, a section of railway track, a first relay provided with a holding circuit including a front contact thereof, means responsive to the presence of a train in said section for de-energizing said first relay, a pick-up circuit for said first relay including a front contact of a normally de-energized slow acting relay, and a circuit for said slow acting relay controlled by a back contact of said first relay, and signaling apparatus controlled by said slow acting relay.
23. In combination, a section of railway track, a first relay provided with a holding circuit including a front contact thereof, means responsive to the presence of a train in said section for de-energizing said first relay, a pick-up circuit for said first relay including a normally open contact of an auxiliary relay, means for causing operation of said auxiliary relay to close said normally open contact when the first relay opens and to open said normally open contact when the first relay closes, the operation of said auxiliary relay to open said normally open contact requiring a considerable interval of time, and signaling apparatus controlled by said auxiliary relay.
24. In combination, a section of railway track, a first relay provided with a holding circuit including a front contact thereof, means responsive to the presence of a train in said section for de-energizing said first relay, a pick-up circuit for said first relay including a normally open contact of a slow acting relay, means for causing operation of said slow acting relay to close said normally open contact when said first relay opens and to open said normally open contact when said first relay closes, and signaling apparatus controlled by said slow acting relay.
25. In combination, a track circuit including a track relay connected with the rails through a front contact thereof, a branch around said front contact including a normally open contact of a slow acting relay, means for causing operation of said slow acting relay to close said normally open contact when the track relay opens and to open said normally open contact when the track relay closes, and signaling apparatus controlled jointly by said track relay and said slow acting relay.
26. In combination, a section of railway track, a first relay provided with a holding circuit including a front contact thereof, means responsive to the presence of a train in said section for de-energizing said first relay, a pick-up circuit for said first relay including a normally open contact of a slow acting relay, means for causing operation of said slow acting relay to close said normally open contact when said first relay opens and to open said normally open contact when said first relay closes, and signaling apparatus controlled jointly by said first relay and said slow acting relay.
